US00D753199S

(12) **United States Design Patent**
Hynek et al.

(10) **Patent No.:** **US D753,199 S**
(b4) **Date of Patent:** **** Apr. 5, 2016**

(54) **SLIDING SHIELD FOR A LATHE**

(71) Applicants: **Martin Hynek**, Plzen (CS); **Miroslav Grach**, Plzen (CS); **Petr Votapek**, Utechovicky (CS); **Jitka Bezdekova**, Pelhrimov (CS)

(72) Inventors: **Martin Hynek**, Plzen (CS); **Miroslav Grach**, Plzen (CS); **Petr Votapek**, Utechovicky (CS); **Jitka Bezdekova**, Pelhrimov (CS)

(73) Assignee: **ZAPADOCESKA UNIVERZITA V PLZNI**, Plzen (CZ)

(**) Term: **14 Years**

(21) Appl. No.: **29/512,278**

(22) Filed: **Dec. 18, 2014**

(51) LOC (10) Cl. **15-09**

(52) U.S. Cl.

USPC **D15/130**

(58) **Field of Classification Search**

USPC D15/122, 127, 128, 129, 130

See application file for complete search history.

Primary Examiner — Patricia Palasik

(57) **CLAIM**

The ornamental design for a sliding shield for a lathe, as shown and described.

DESCRIPTION

FIG. 1 is a perspective front view of a sliding shield for a lathe showing my new design;

FIG. 2 is a front elevational view thereof;

FIG. 3 is a left side elevational view thereof;

FIG. 4 is a right side elevational view thereof;

FIG. 5 is a bottom plan view thereof;

FIG. 6 is a rear elevational view thereof;

FIG. 7 is a top plan view thereof; and,

FIG. 8 is a perspective rear view thereof.

The broken lines in the drawings depict unclaimed environmental subject matter.

1 Claim, 8 Drawing Sheets
